EDWIN C. DAVIS, OF ELYRIA, OHIO, ASSIGNOR OF ONE-HALF TO FRANCIS J. COMERFORD
AND WALTER G. COMERFORD, BOTH OF ELYRIA, OHIO.

AUTOMATIC SHUT-OFF VALVE FOR GAS-BURNERS.

1,250,984.

Specification of Letters Patent.

Patented Dec. 25, 1917.

Application filed November 20, 1915, Serial No. 62,478.

To all whom it may concern:

Be it known that EDWIN C. DAVIS, a citizen of the United States, residing at Elyria, in the county of Lorain and State of Ohio, has invented certain new and useful Improvements in Automatic Shut-Off Valves for Gas-Burners, of which the following is a specification.

This invention relates to new and useful improvements in automatic shut-off valves for gas burners.

The object of this invention is to provide a valve of this type especially designed for shutting off the flow of gas from the service pipes of a building to a gas burner or jet after the pressure in the gas main has fallen below a predetermined pressure.

My invention, therefore, consists in the features of construction and combination of parts as described in the specification, pointed out in the claim, and illustrated in the accompanying drawings.

Figure 1 is a central vertical section showing the floating plunger raised open and in the position it will maintain when the pressure is normal. Fig. 2 is a similar view showing the valve closed, and Fig. 3 is a vertical section of the auxiliary valve shown double size, the purpose of which is to provide a means of opening the valve after it has become closed.

Again, referring to the drawings, the body portion 4 of the valve casting is divided into two chambers, A. and B. by a diaphragm 35 or wall 13, the said chambers being connected by the opening 14, and designed to be closed when the floating plunger rests upon its seat 12, in the position as shown in Fig. 2.

The said plunger 3 is contained within the barrel 2 which is covered with a threaded cap 1.

An auxiliary valve and valve stem 8 passes through the threaded cylindrical barrel or bushing 9 from beneath and the said bushing has a seat at its upper end in the inlet passage for the valve 8. The internal diameter of this barrel is always sufficiently greater than the external diameter of the valve stem 45 to permit a ready passage of gas between the same and through the opening 16 when the valve is raised in the position as shown by dotted lines in Fig. 2, and into chamber B by means of port or opening 10. Leakage is 50 prevented around the lower end of the aux-

iliary valve stem by the packing nut threaded on to barrel or bushing 9 and having an opening permitting the passage of the valve stem at X.

The inlet pipe C discharges into chamber 60 or passage A and the outlet pipe D connects with chamber B.

The operation is as follows:—

When the pressure of the gas main is normal the cylindrical plunger 3 will be raised 65 in position as shown in Fig. 1 and sustained by the gas pressure upon the surface of the lower closed end, marked 15, so that when the gas falls noticeably below a predetermined pressure the plunger 3 will fall under 70 the influence of gravity to a position as shown in Fig. 2. This effectually closes the passage 14 between chambers A and B and stops the flow of the gas from the inlet, whether or not the pressure again becomes 75 normal.

The auxiliary valve 8 at this time is used to effect the opening of this plunger 3 by admitting gas beneath the same as follows:

When the valve 8 by hand manipulation is 80 raised to a position as shown by dotted lines at 8 in Fig. 2 the pressure from the inlet is exerted upon the surface of the lower end 15 of plunger 3 by way of opening 16 and port 10 thus causing it to open and in which 85 position it is maintained until the gas pressure again drops below the predetermined normal. Thereupon the operation is repeated. The plunger necessarily is made of a suitably light material, so as to respond to 90 the changes in gas pressure.

In an automatic shut-off valve for gas burners what I claim as new is:—

The combination of a casing having a fluid inlet and outlet, and a diaphragm 95 between said inlet and outlet having an opening therein, and a vertically disposed plunger adapted to be seated by gravity, and to close said opening when fluid pressure is decreased materially below normal, said 100 plunger being normally sustained immediately above said opening by fluid pressure, and so positioned as to remain seated upon said opening without regard to the subsequent increase of pressure from the inlet, 105 and an auxiliary valve mechanism comprising a threaded cylindrical tube extending through the wall of the casing from the bottom and outside thereof, into the inflow space above said diaphragm, and having a 110

valve seat at its top, a valve for said seat having a stem extending through said barrel or tube, and exposed at its lower end for hand manipulation, said tube having an orifice in its side exposed to the outlet chamber beneath said diaphragm adapted to utilize the gas pressure from above said diaphragm into the space beneath the same

to unseat said plunger and restore the parts to original working position.

In testimony whereof I affix my signature in presence of two witnesses.

EDWIN C. DAVIS.
